DESIGN FOR A COMBINED FREEZER AND DISPENSER FOR FROZEN FOODS

Walter von Lindeck, Los Angeles, Calif.

Application February 15, 1947, Serial No. 136,941

Term of patent 3½ years

(Cl. D52—2)

To all whom it may concern:

Be it known that I, Walter von Lindeck, a citizen of Germany, residing at Los Angeles, in the county of Los Angeles and State of California, have invented a new, original, and ornamental Design for a Combined Freezer and Dispenser for Frozen Foods, of which the following is a specification, reference being had to the accompanying drawing, forming part thereof.

Fig. 1 is a perspective view taken from the right of a combined freezer and dispenser for frozen foods, showing my new design;

Fig. 2 is a perspective view taken from the left;

Fig. 3 is a rear elevation; and

Fig. 4 is a top plan view.

I claim:

The ornamental design for a combined freezer and dispenser for frozen foods, as shown.

WALTER von LINDECK.
